UNITED STATES PATENT OFFICE.

ERNEST R. ERICKSON, OF DES MOINES, IOWA, ASSIGNEE TO C. E. ERICKSON COMPANY, INC., OF DES MOINES, IOWA.

RADIATOR PROTECTOR.

Application filed April 14, 1926. Serial No. 102,005.

The purpose of my invention is to provide a radiator protector of very simple and very inexpensive construction.

More particularly, it is my object to provide a very inexpensive radiator structure having parts so constructed and arranged that it can readily and easily be adapted for mounting on radiators of a great variety of makes of cars.

With these and other objects in view, my invention consists in the construction, arrangement and combination of the various parts of my radiator protector, whereby the objects contemplated are attained, as hereinafter more fully set forth, pointed out in my claims, and illustrated in the accompanying drawings, in which:

Figure 1 is a front elevation of a motor vehicle equipped with a radiator protector embodying my invention.

Figure 2 is a detail, sectional view taken on the line 2—2 of Figure 1.

Figure 3 is a detail, sectional view taken on the line 3—3 of Figure 1.

Figure 4 is a front elevation of the upper right-hand corner of the radiator protector, parts being broken away.

Figure 5 is a similar view of the lower left-hand corner of the protector, parts being broken away.

Figure 6 is a perspective view of one of the adjustable fastening devices for supporting the protector on a radiator; and

Figure 7 is a perspective view of another of the fastening devices for supporting the protector on a radiator.

In the drawings filed herewith, I have used the reference numeral 10 to indicate generally a motor vehicle having the fenders 11, front lamps 12 and the radiator indicated generally by the numeral 13.

I have used the numeral 14 to indicate the side portions of the radiator frame or shell and the numeral 15 to indicate the lower part of the frame or shell.

My improved radiator protector comprises a sheet or the like 16 of heavy cardboard or fiber or other suitable material. The sheet 16 is preferably longer than it is wide and is designed to fit over and in front of the lower part of the radiator.

The radiator protector sheet 16 is long enough to cover the lower part of the radiator of almost any standard make of car.

The purpose is to make the sheet 16 of some inexpensive pasteboard or fiber material.

In order to give this sheet proper strength, I reinforce it at the ends by means of a channel-shaped metal reinforcing strip 17. A similar channel-shaped reinforcing strip 18 receives the bottom or lower edge of the sheet 16. I bind the top edge of the sheet 16 with a binder and reinforcing member similar to the reinforcing binder strips 17 and 18, except, however, that the upper channel-shaped binder strip 19 is formed at its upper part with a bead or roll 20, as particularly illustrated in Figure 2.

The sheet 16 thus reinforced is intended to be adapted for use on a great variety of makes of cars. The sheet 16 may be used to carry advertising or the like.

In order that it may be conveniently used on cars of different makes and for radiators of different sizes and shapes, I provide suitable means adjustably carried by and connected with the sheet 16 for mounting the sheet 16 on the radiator.

It may be mentioned that nearly all radiators have shells or frames including the upright side portions 14 and the bottom portions 15, which tend to overlie the front part of the radiator proper 13.

I provide therefore for the lower edge of the sheet 16 a pair of supporting clamps, one of which is shown in Figure 7, indicated generally by the reference character A. The clip A comprises an upwardly opening channel-shaped portion 21, which receives the lower edge of the sheet 16 having the binding strip 18, as shown for instance in Figure 2. At the rear part of the channel-shaped member 21 of the clip A is a downwardly projecting tab 22, shown clearly in Figure 5 and in Figure 2, which is slipped behind the radiator shell member 15 at the bottom and in front of the radiator 13, in the manner illustrated in Figure 2.

The lower edge of the strip 16 is firmly gripped by the walls of the channel-shaped portion 21 of the clip A.

For connecting the upper part of the sheet 16 with the radiator, I provide a pair of clips B, one of which is illustrated in Figure 6. These clips B, each comprise a downwardly opening channel 23, each having an enlarged portion 24 at its upper part designed to snugly receive the roll 20 of the reinforcing and binding strip 19.

The channel-shaped portion 23 is of resilient material, so as to yieldingly grip the upper edge of the sheet 16.

Each clip B has at one end a tab 24^b projecting longitudinally of the sheet 16.

The clips A and B are slidable on the sheet 16.

The clips B are slid until the tabs 24^b clear the upright radiator shell portions 14 at the sides of the radiator and are then slid longitudinally on the sheet 16 until the tabs 24^b, which are inclined rearwardly away from the sheet 16 as at 24^a, and then laterally in a plane parallel with that of the sheet 16, as shown in Figure 3, have their latter portions projected behind the upright shell members 14, between the front portions thereof and the radiator proper 13.

The channel-shaped portion 23 of the clip B grips the roll 20 and the reinforcing and binding strip 19 resiliently so as to retain its position on the sheet 16 wherever it may be adjusted.

It will thus be seen that on account of the adjustability of the clips A and B on the sheet 16, my radiator protector may be mounted upon a great variety of radiators of varying width.

The clips A are simply slid inwardly from the ends of the sheet 16 until they are properly spaced. Similarly the clips B are slid inwardly at the upper edge of the sheet 16. The radiator protector is then slipped into position with the tabs 22 between the front parts of the shell portion 15, and the radiator proper, and the clips B are then slid endwise on the sheet 16, until the tabs 24^b slide between the front portions of the radiator shell end members 14 and the radiator proper. The clips because of their resiliency will remain in any of their adjusted positions.

Even if the sheet 16 is a little longer than the width of a radiator, the protector may still be readily and easily mounted on such a radiator.

It is therefore obvious that I have provided a radiator protector of very light weight and inexpensive material, properly reinforced at its ends and top and bottom edges.

For mounting this protector on a radiator, I have provided the sliding, resilient members A capable of being adjusted from end to end on the strip 16 and having a tab 22, which may be readily mounted on any ordinary

radiator. The top reinforcing or binding strip 19 for the protector has the roll or bead 20, and the upper clips B have the corresponding receiving rolls 24, so that no up or down movement of the clip on the sheet 16 can occur.

The weight of the sheet holds it down and snugly received in the channel-shaped portions 21 of the clips A.

Some changes may be made in the details of construction and arrangement of the parts of my improved radiator protector, and it is my intention to cover by my claims any modified forms of structure or use of mechanical equivalents, which may be included within the scope of my invention and of my claims.

I claim as my invention:

1. In a radiator protector, a sheet having at its top edge a thickened portion, a fastening element for said top portion, comprising a channel-shaped member having at its deepest part an enlarged portion to receive said thickened portion, said fastening element having means for connecting it with a radiator.

2. In a radiator protector, a sheet having at its top edge a thickened portion, a fastening element for said top portion, comprising a channel-shaped member having at its deepest part an enlarged portion to receive said thickened portion, said fastening element having means for connecting it with a radiator, comprising a tab projecting rearwardly and then laterally, substantially as shown.

3. In a radiator protector, a sheet having at its top edge a thickened portion, fastening elements for said protector comprising members slidably mounted on said thickened portion and adapted to be connected with a radiator.

4. In a radiator protector, a sheet having at its top edge a thickened portion, fastening elements for said protector comprising members slidably mounted on said thickened portion and adapted to be connected with a radiator, comprising channel-shaped resilient members with enlarged portions at their deepest parts to receive said thickened portions.

5. In a radiator protector, a sheet having at its top edge a thickened portion, fastening elements for said protector comprising members slidably mounted on said thickened portion and adapted to be connected with a radiator, comprising channel-shaped resilient members with enlarged portions at their deepest parts to receive said thickened portions, and laterally projecting tabs, said fastening elements being slidable on said sheet.

6. In a radiator protector, a sheet having fastening devices slidably mounted on its lower edge and provided with downwardly projecting tabs, said sheet having fastening

devices slidably mounted on its upper edge having laterally projecting tabs.

7. In a protector, a sheet having fastening devices slidably mounted on its lower edge and provided with downwardly projecting tabs, said sheet having fastening devices slidably mounted on its upper edge having

laterally projecting tabs, said upper fastening devices being mounted on said sheet for lateral sliding movement and in such manner as to prevent vertical sliding movement thereon. 10

ERNEST R. ERICKSON.
